(57) **CLAIM**

The ornamental design for a handbag (torquay crosta), as shown and described.

DESCRIPTION

FIG. 1 is a front perspective view of a handbag (torquay crosta) showing my new design;

FIG. 2 is a front elevational view thereof;

FIG. 3 is a rear elevational view thereof;

FIG. 4 is a left side elevational view, the right side being a mirror image thereof;

FIG. 5 is a top plan view thereof; and,

FIG. 6 is a bottom plan view thereof.

The background and surface on which the handbag is displayed in the photographs and the shadows and reflections form no part of the claimed design.

1 Claim, 6 Drawing Sheets
